UNITED STATES PATENT OFFICE.

HERMAN GREEDER, OF SCIO, OHIO.

CLEANING AND WAXING PAD.

SPECIFICATION forming part of Letters Patent No. 769,541, dated September 6, 1904.

Application filed June 19, 1903. Serial No. 162,263. (No model.)

To all whom it may concern:

Be it known that I, HERMAN GREEDER, a citizen of the United States, residing at Scio, in the county of Harrison and State of Ohio, have invented a new and useful Cleaning and Waxing Pad, of which the following is a specification.

The present invention relates to a simple article of manufacture to be employed in cleaning and waxing the operative faces of laundry and tailors' irons.

One object is to provide a pad which will contain a comparatively great quantity of waxing composition and will mechanically deliver the same to the iron without waste, at the same time cleaning said iron of all dust, dirt, and adhering matter.

Another object is to provide a pad either side of which can be used indiscriminately.

A still further object is to provide a disinfectant so incorporated with the wax that it will be given off with the exudation of the latter; furthermore, to provide a structure that will not be burned or scorched by the heated irons.

A simple form of construction is illustrated in the accompanying drawings, wherein—

Figure 1 is a perspective view of a pad constructed in accordance with the present invention. Fig. 2 is a sectional view through the same.

Similar reference-numerals indicate corresponding parts in both figures of the drawings.

In the embodiment illustrated the pad is oblong in form and comprises a body 5, made up of suitable absorbent material—as, for instance, separate sheets of unsized or blotting paper. This body is impregnated with any well-known waxing composition employed in waxing irons. Incorporated with the waxing composition are disinfectants, such as formaldehyde, oil of eucalyptus, and the like. In preparing the body the wax is first melted and the disinfectants are mixed with the same. The sheets are then dipped one or more times, as may be required, into the melted compound and are allowed to cool. The result is that the wax and disinfectants are thoroughly commingled and completely impregnate the body.

The body as thus constituted is inclosed by a porous casing 6, which is preferably of some light cloth, such as muslin, thoroughly porous to permit the exudation of the wax and sufficiently rough in its texture to clean the faces of the irons of all adhering foreign matter. The casing 6 completely surrounds the body and constitutes the outer faces of the same. Either face of the pad can therefore be employed, as will be readily understood. In order to prevent the fabric becoming scorched or burned by the heated irons, the casing is preferably impregnated with a fireproof composition—as, for instance, sodium tungstate.

In use the iron is simply passed over one face of the pad, whereupon said iron will be cleaned. At the same time the heat will melt the wax sufficiently to permit its exudation through the casing, this casing, however, taking up and preventing a too free flow of the wax. When the wax is thus softened, the disinfectant will be released therefrom and will be given off. The fireproof composition prevents all scorching of the pad and also protects the body, with its incorporated waxing composition. The wax will be fed slowly by capillary attraction through the uppermost face of the casing, and after practically all the material has been taken from the upper portion of the body the pad may be inverted and the opposite side used in the same manner.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. A pad of the class described comprising a flat absorbent body made up of blotting-paper saturated with waxing material; and a fireproof porous casing completely enveloping the body, said casing permitting the passage therethrough of the waxing material when a

heated iron is passed thereover, and said pad being reversible to present either side to the action of the iron.

2. A pad of the class described, comprising a body formed of absorbent paper, commingled wax, eucalyptus-oil, and formaldehyde contained in the paper, a fabric casing covering both sides of the body, and sodium tungstate impregnating the casing to render the same fireproof.

3. A pad of the class described, comprising an absorbent body, a commingled waxing and disinfecting composition incorporated in the

body, and a fireproof porous casing covering the opposite faces of the body and permitting ¹⁵ the passage therethrough of the composition from the body when a heated iron is passed over either of the faces.

In testimony that I claim the foregoing as my own I have hereto affixed my signature in ²⁰ the presence of two witnesses.

HERMAN GREEDER.
